(57) **CLAIM**

The ornamental design for a display screen or portion thereof with graphical user interface, as shown and described.

DESCRIPTION

FIG. 1 is a front view of a display screen or portion thereof with graphical user interface showing my new design; and, FIG. 2 is a front view of the graphical user interface of FIG. 1, in which a mobile terminal in broken lines is provided to illustrate an example environment.

The broken line showing of the mobile terminal, and the text/words, numbers, symbols, and otherwise images in the graphical user interface represents portions of the display screen or portion thereof with graphical user interface which form no part of the claimed design.
